UNITED STATES PATENT OFFICE.

AUGUSTUS H. DURBUR, OF BROOKLYN, NEW YORK.

DESIGN FOR A MOLDING FOR PICTURE-FRAMES.

SPECIFICATION forming part of Design No. 23,153, dated March 27, 1894.

Application filed February 3, 1894. Serial No. 499,031. Term of patent 3½ years.

To all whom it may concern:

Be it known that I, AUGUSTUS H. DURBUR, a citizen of the United States, residing at Brooklyn, in the county of Kings and State of New York, have invented and produced a new and original Design for a Molding for Picture-Frames or the Like, of which the following is a specification, reference being had to the accompanying drawings, forming part ⁵ thereof.

Figure 1. is a front view of a molding showing my design; Fig. 2. a corner view of the same.

My design consists of an ornamentation of ¹⁵ leaves in relief for a molding suitable for picture frames or the like.

The leading features of the design are ornamental leaves in relief occupying the full width of the molding, with an ornament B

between them, said ornament B having leaf ²⁰ petals, and the leaf arrangement in relief at the corner or corners substantially as shown.

A are the large leaves in relief which occupy the full width of the molding. Between the large leaves A is a semi-circular ornament ²⁵ B composed of flower petals united at their base. The corner is formed of three leaves C united at their base and diverging from each other.

I claim—

The design for a molding for picture frames, substantially as herein shown and described.

Signed at the city of New York, State of New York, this 2d day of February, 1894.

AUGUSTUS H. DURBUR.
